UNITED STATES PATENT OFFICE

2,507,011

HEATING DEVICE

Arthur G. Hebert, Manchester, N. H.

Application August 12, 1947, Serial No. 768,232

3 Claims. (Cl. 237—56)

1

This invention relates to heating apparatus, and more particularly to a heating attachment for use in conjunction with the hot water heater of a kitchen range.

A main object of the invention is to provide a novel and improved heating unit adapted to be employed in conjunction with a conventional water heater, said heating unit being very simple in construction, easy to install and economical in operation.

A further object of the invention is to provide an improved air heating and air circulating attachment adapted to be installed in the hot water line of a water heating system, said attachment being inexpensive to manufacture, compact in size, and neat in appearance.

Further objects and advantages of the invention will become apparent from the following description and claims, and from the accompanying drawings, wherein:

Figure 1 is a perspective view of a conventional hot water heating system showing an air heating unit constructed in accordance with the present invention installed in the hot water line of the system.

Figure 2 is a longitudinal cross-sectional detail view taken through the air heating unit of Figure 1.

Referring to the drawings, 11 designates a conventional kitchen range. Designated at 12 is a hot water boiler. The water heating coil 13 is mounted in the fire chamber of the range 11. The cold water inlet pipe is shown at 14 and is connected to the water supply.

Connected between the hot water outlet pipe 15 from heater coil 13 and the hot water inlet pipe 16 of boiler 12 is the air heater 17, said heater comprising a cylindrical shell 18 secured to the pipes 15 and 16 and provided at its ends with air screens 19 and 20. Mounted in the shell 18 is the radiator coil 21, the ends of coil 21 being connected to the respective hot water pipes 15 and 16 so that the hot water from heater coil 13 circulates through the radiator coil 21. Supported in semi-circular collar brackets 22, 22 secured to one end of shell 18 by respective arms 23, 23 carried by said brackets is an electric motor 24, said motor being clamped in said collar brackets and being substantially coaxial with shell 18. Secured on the motor shaft is a propeller 25. When motor 24 is energized, propeller 25 blows a current of air through the intake screen 19 and through the radiator coil 21, the air being heated by contact with the coil 21 and emerging from the shell 18 at the outlet screen 58

2

20. The heated air thus is circulated through the room by the draft created by the fan propeller 25.

The unit above described is very economical in operation in that it utilizes heat which would otherwise be retained in the water in boiler 12 even when the water is not used, and circulates heated air through the room whereby the room is rapidly warmed and is maintained at a comfortable temperature as long as the range 11 is in operation or as long as the water in the hot water line is at an elevated temperature.

While a specific embodiment of a heating apparatus adapted to be attached in a conventional water heating system has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. The combination with a kitchen range and associated hot water tank, said range having an internal water heating coil having an external pipe leading directly to said tank, of a radiator coil connected between the ends of said external pipe intermediate said range and said tank and exposed to the atmosphere of the space in which said range and tank are located, a tubular heat concentrating and guiding housing surrounding said radiator coil and supportably mounted on said external pipe, and a fan mounted at one end of said housing for moving air from said space through said housing in contact with said radiator coil.

2. The combination with a kitchen range and associated hot water tank, said range having an internal water heating coil having an external pipe leading directly to said tank, of a radiator coil connected between the ends of said external pipe intermediate said range and said tank and exposed to the atmosphere of the space in which said range and tank are located, a tubular heat concentrating and guiding housing surrounding said radiator coil and supportably mounted on said external pipe, and a fan mounted at one end of said housing for moving air from said space through said housing in contact with said radiator coil, said radiator coil being of substantially the same diameter as said external pipe, said radiator coil and said external pipe forming a continuous conduit of substantially uniform diameter.

3. The combination with a kitchen range and

associated hot water tank, said range having an internal water heating coil having an external pipe leading directly to said tank, of a radiator coil connected between the ends of said external pipe intermediate said range and said tank and exposed to the atmosphere of the space in which said range and tank are located, a tubular heat concentrating and guiding housing surrounding said radiator coil and supportably mounted on said external pipe, and a fan mounted at one end of said housing for moving air from said space through said housing in contact with said radiator coil, said radiator coil comprising a plurality of axially arranged convolutions and said tubular housing concentrically surrounding said convolutions.
